JAMES C. WOODSON, OF MANSFIELD, OHIO, ASSIGNOR TO WESTINGHOUSE ELECTRIC & MANUFACTURING COMPANY, A CORPORATION OF PENNSYLVANIA

CONVEYER FURNACE

Application filed March 17, 1930. Serial No. 436,369.

My invention relates to furnaces and particularly to conveyer-type furnaces.

An object of my invention is to provide a relatively strong furnace structure that shall ensure the maintenance of the initial relative positions of the various parts of the furnace structure under normal varying operating conditions.

Another object of my invention is to provide a double-chamber furnace structure having an intermediate wall, including a plurality of arches, that is shorter than the outside walls and is provided with means for preventing excessive elongation.

Another object of my invention is to provide a relatively simple overhanging roof structure of refractory material that shall be so constructed as to be substantially rigid under the various conditions of operation.

Another object of my invention is to provide a roof structure for a conveyer-type furnace having at least one slot in the roof thereof which shall include interfitting refractory slabs of fire clay and an armored concrete bonding mass located thereon as well as resilient supporting means for the refractory roof slabs.

Another object of my invention is to provide a slot-closure means supported by the stationary furnace structure and moved by the conveyer over the walls of the slot, in combination with slot seals to prevent dust from dropping through the slot upon work being treated in the furnace.

In practicing my invention, I provide a relatively long furnace structure including a double chamber having suitable heating means in the central portion of such structure, as well as pre-heating chambers at the respective ends of the heated chambers, the intermediate wall being solid in the heated portion of the furnace and being relatively open and including arches in the pre-heating portions.

Longitudinally-extending slots are provided in the roof structure, and an endless conveyer or a plurality of such conveyers are supported by a skeleton-frame structure associated with the refractory structure of the furnace, the conveyer chains being provided

with depending material-supporting rods which extend into, and move through the respective furnace chambers.

In the drawings,

Figure 1 is a top plan view of one-half of a furnace assembly embodying my invention, a portion only of the conveyer chains being illustrated.

Fig. 2 is a view, in vertical longitudinal section, taken on the line II—II of Fig. 1,

Fig. 3 is a view, in vertical lateral section, through a furnace embodying my invention, taken on the line III—III of Fig. 2,

Fig. 4 is a view, in vertical lateral section, taken on the line IV—IV of Fig. 2,

Fig. 5 is a view, in vertical lateral section, taken on the line V—V of Fig. 2,

Fig. 6 is a fragmentary view, in vertical lateral section, on an enlarged scale, to show the furnace construction immediately adjacent a slot,

Fig. 7 is a fragmentary view, in vertical lateral section, of a portion of the furnace structure to show the construction of the slot closure means and of the material-supporting means,

Fig. 8 is a view, in side elevation, of a material-supporting bar,

Fig. 9 is a view, in perspective, of two refractory fire-clay roof slabs,

Fig. 10 is a view, in side elevation, of a hook holder, and,

Fig. 11 is a view, in end elevation, of a hook holder.

Referring more particularly to Figs. 1 and 2 of the drawings, I have there illustrated, in top plan view and in vertical longitudinal section, respectively, a double-heating-chamber conveyer-type furnace particularly adapted for enameling work. The furnace structure embodies a plurality of vertical spaced metal members 11 which may be of I-beam shape in lateral section and which may have their lower ends embedded in a concrete base 12 which extends below substantially all of the furnace.

Horizontally extending metal members 13, which may also be of I-beam shape, have their ends connected, by suitable gusset plates 14, to the upper ends of the members 11. The

location of the vertical members 11 is, of course, adapted to the various wall thickness of the different portions of the furnace, as will be hereinafter pointed out more particularly in detail, and as is shown in the top plan view in Fig. 1 of the drawings.

Referring also to Figs. 3, 4 and 5, the furnace proper includes a floor 16, vertical side walls 17 and 18 and an intermediate-wall 19, the side and bottom wall structures including an inner layer 21 of high-temperature-resisting refractory bricks or blocks, and the intermediate wall being constructed entirely of such high-temperature-resisting bricks.

15 Heat-insulating refractory material is then located outside of the inner layer 21 which may consist of a plurality of bricks or blocks of proper refractory material or it may be made of monolithic material, as may be found desirable. Powdered refractory heat-insulating material 23 is located between the outer layer of solid heat-insulating material and a metal casing 24 which is, in turn, supported by the skeleton metal-frame structure hereinbefore described.

Referring more particularly to Figs. 3 and 4 of the drawings, I have there illustrated a roof structure which I have found to be highly efficient in operation and which is constructed to permit of maintaining the initial positions of all of the component parts with a minimum amount of shifting or variation in these relative positions under the varying conditions of operation of the furnace. To this end, the roof proper consists of a plurality of inter-fitting slabs or blocks 26 of fire clay, shown more particularly in Fig. 9 of the drawings. As there shown, each slab or block is of substantially wedge shape and is provided with an upstanding flange 27 at its thicker edge.

40 A groove 28 is provided in one side, and a corresponding and cooperating tongue 29 is provided at the other side so that the adjacent slabs 26 may be interlocked, as shown. A vertical semi-cylindrical recess 31 is provided at the side and adjacent to the forward side of each slab, for a purpose to be hereinafter set forth. A lateral groove 32 is provided in the upper face of each slab or block 26 and adjacent to its thin edge, for a purpose to be hereinafter set forth in detail.

The thick ends of the slabs 26 so rest upon one of the walls of the furnace as to overhang the respective furnace chambers, which have been designated as 33 and 34 in Fig. 3 of the drawings. While the general shape of the furnace chambers may vary to a slight degree, the aligned furnace chambers are of substantially the same general contour in lateral section.

Referring to Fig. 3 of the drawings, a monolithic mass 36 of concrete overlies the slabs 26, that rests upon the wall 17, this mass 36 interfitting with the flanges 27 on the re-

spective slabs 26, as well as resting upon the upper edge portion of the outer part of the solid wall 17. In order to strengthen the mass 36, I provide an armor in the shape of a coarse wire screen 37.

70 Similar slabs 26 are located with their thick ends on the intermediate wall 19 in oppositely extending and abutting relation, as is shown in Figs. 3 to 5, inclusive. A monolithic mass 38 of concrete is provided over the major portion of each of the sets of abutting slabs 26, and an armor 39 is provided therein, in substantially the manner, and for the purpose, hereinbefore described for roof structure.

80 A similar mass 36a of armored concrete is provided over the side wall 18 and, as these roof portions are alike, further description of this part of the structure is unnecessary. The granular refractory heat-insulating material 23 extends over the upper surface of the monolithic slabs 36, and similar granular heat-insulating material is provided over the central monolithic mass 38.

85 The sets of slabs 26, resting, respectively, upon one of the outside walls and upon the intermediate wall and extending toward each other, have their inner ends spaced apart a predetermined distance in order to cooperate with other elements to be hereinafter described to provide a longitudinally-extending slot in the roof structure, there being two such slots 41 and 42 to correspond to the number of heating chambers located in side-by-side relation.

90 Relatively thin blocks 43 of refractory material extend vertically and longitudinally of the furnace structure adjacent to the slots, their lower edges being provided with tongue portions 44 which fit into the grooves 32 of the slabs 26.

95 Fig. 6 is a view, on an enlarged scale, of this and other cooperating and adjacent portions of the furnace structure and it will be noted that the concrete mass 36 on the one hand and the concrete mass 38 on the other side extend up to the members 43 and will, therefore, be bonded therewith during the course of manufacture of this part of the roof structure, in a manner well known in the art.

100 A plurality of box-like frames, each of skeleton construction, are provided immediately above the roof of the furnace, there being an intermediate frame structure 46 and two outside and similar frame structures 47. The intermediate frame structure 46 includes two angularly disposed cross braces 48 and 49, vertical metal members 50 and 51 and a lower horizontal metal member 52, all of these metal members being suitably riveted together, as shown in Figs. 3 and 4 of the drawings.

105 The outside frames 47 include depending vertical members 53, a diagonal bracing 110

member 54 and a horizontal lower member 56. The horizontal members 52 and 56 inter-fit with the roof structure to a certain degree, that is, one of the webs of the angle bars or the T-bars constituting these elements may be partially embedded in the refractory heat-insulating material at the top of the roof proper.

Longitudinal metal members 58 are provided adjacent to the upper edges of the respective slots 41 and 42, each of these members being of substantially Z-shape in lateral section, as may best be understood by reference to Fig. 6 of the drawings. The upper vertical webs of the respective members 58 may be riveted to the lower ends of the corresponding members 53, and their lower webs are in operative engagement with the upper edges of the members 43 in order to so definitely locate and hold them in their proper operative and spaced positions relative to each other as to define a longitudinally extending slot of a predetermined width.

It may be noted that the cross braces 48, 49 and 54 in the respective skeleton frames are properly located to assist in supporting the vertical members 51 and 53 to cooperate with the roof structure and, more particularly, to prevent any weight from being placed upon the refractory roof structure.

As a further means for supporting the projecting or overhanging roof structures, I have provided resilient supporting means including a plurality of rods 61 having enlarged heads 62 at their lower ends, a plate 63 being located between the head 62 and a pair of adjacent slabs 26, the rods 61 extending through the cooperating grooves 31 provided in adjacent edge portions of the slabs 26.

A structural-steel member 68, which may be of angle-bar shape in lateral section, extends longitudinally of the furnace structure and is riveted or otherwise secured to the members 52 or 56.

A plurality of members 65, each of substantially angle-bar shape, have upper edges of hook shape to engage the upper edge of angle-bar member 68. The upper ends of rods 61 extend through openings in web portions of the members 65, springs 64 being located around their projecting ends. Nuts 66 and washers 67 are provided for the purpose of drawing rods upwardly. The springs 64 permit of relative expansion and contraction of the various portions of the furnace frame-and-roof assembly.

Reference may now be had to Fig. 2 of the drawings and more particularly to the intermediate wall which is designated generally as 66a and which comprises a plurality of arches 67a, each being built of suitable refractory bricks or blocks, in a manner well known in the art, and resting upon refractory bases 68a which, in turn, rest upon the refractory floor structure 16, which may either

be special to the preheating chambers located at each end of the heating chambers hereinbefore set forth or may be common to all of the furnace chambers. As was hereinbefore stated, the intermediate wall 19 is substantially solid, as it is desired to provide two separate heating chambers, while it is necessary to provide communicating chambers located in side-by-side relation if recuperation is to be obtained when the furnace is in operation. Hence, I prefer to provide an intermediate wall structure of substantially the same general character as are the outside wall structures but of an interrupted character, that is, provided with open spaces covered by arches, in order that the heat-treated material, such as members which have had enamel baked thereon, may give up an appreciable portion of their heat to incoming material which is yet to be heat treated or enameled.

The intermediate wall structure, including the central portion 19 and the end portions 66a, is made shorter than are the outside wall portions in order that the extreme outer end portions of the furnace structure may not have any wall intermediate the outside walls. The intermediate wall structure will, of course, expand and, in order that it may not expand to an undesirably high degree and in

order to anchor the ends thereof, I provide a vertical structural metal member, which may be of I-shape in lateral section and is designated by the numeral 71 in Fig. 2 of the drawings, the lower end being anchored in the concrete base 12. A diagonally extending brace 72, which may also be of I-shape in lateral section, is provided and has its upper end suitably secured to the upper end of member 71, while its lower end extends into the concrete base to be firmly anchored therein. It is apparent that any longitudinal expansion of the wall 66a and perhaps also of the wall 19 will be resisted by the brace 72 and at least a portion of this expansion will be taken up by relatively small vertical movements of the individual refractory arches 67a, so that there will not be an excessive or multiplied movement of any part of the wall but rather this movement will be forcibly sub-divided into a plurality of relatively small individual movements of portions of the wall in substantially an upward direction.

The skeleton frames 47 and 48 are spaced apart laterally immediately above the slots 41 and 42, and angle-bar members 76 are provided on the respective vertical members 50, 51 and 53 to constitute a horizontal track for the rollers 77 of a conveyer chain 78, which is shown generally only in Fig. 3 of the drawings. It is to be understood that any suitable or desired form of chain may be employed.

In general, it may be noted that I prefer to employ two separately-actuated chains, one operating or moving over the slot 41 and the

other moving over the slot 42, drums 79 and 79 α being provided at each end of the furnace around which the conveyer chains may turn or move, in a manner well known in the art. I have illustrated the sheaves or drums 79 and 79 α as provided with gear teeth in order that they may be properly driven by a suitable actuating means (not shown in detail in the drawings).

30 It may be noted that alternately opposite ends of the furnace will be effective as loading stations for placing material to be heat treated in the furnace on the respective oppositely moving conveyer chains, the stations for removing this material being located at the alternately opposite corners of the furnace structure.

While it is within the province of my invention to employ a single conveyer chain, the two portions of which move over the respective slots 41 and 42 in opposite directions, I prefer to employ two separate chains, as this permits of operating the two chains at different speeds, whereby it is possible to adapt the furnace to a wider range of work. This is for the reason that it is frequently possible to vary the speed of movement of a conveyer chain in accordance with the type of enamel coating which is being heated in the furnace, so that the use of two separate conveyer chains permits of obtaining a greater output from any given furnace.

35 A plurality of hook holders 81 are suspended, from the conveyer chain, at spaced intervals, these being shown in detail in Figs. 10 and 11 of the drawings. As there shown, each hook holder includes two similar and opposed portions 82 which are substantially rectangular in contour, the upper ends of the two members 82 being provided with cooperating lugs 83 and 84 spaced apart to provide a recess 86 between them, into which the enlarged lower ends of the link members 87 are fitted. A pair of bolts 88 extend through the 40 two opposed members 82 to securely clamp hook supporting rods to the rods 87. The lower ends of the members 82 are provided with inwardly projecting lugs 89 from which are supported depending rods 91, shown in detail in Fig. 7 of the drawings. The upper ends of the rods 91 are enlarged to substantially rectangular shape, and an opening may be provided therethrough to fit over or around the plurality of lugs 89 in order that the rods 55 may have a slight swinging movement longitudinally of the conveyer chain. The upper ends of the rods 91 are of such shape as to cooperate with the lower surfaces of the lugs 84 to prevent excessive longitudinal swinging movement for the reason that any uneven or jerky movement of the conveyer chain should be transmitted in the least possible degree to the material supported adjacent to the lower ends of the rods.

60 65 Links 93 extend between adjacent rods 91

and are supported upon foot plates or blocks 94 with which the lower ends of the rods are provided. Cooperating pins and sockets may be provided in the respective members 94 and 93 in order to ensure that the links 93 shall not become disengaged from the rods 91.

70 The material itself may be supported from cross bars 96, shown more particularly in Fig. 8 of the drawings, which are of such construction as to be easily and quickly mounted on or above the links 93 and to extend laterally therefrom. A plurality of holes 97 are provided in the members 96 to receive the upper ends of metal hooks 98 upon which the material to be enameled may be hung. As the sizes and shapes of the articles to be enameled or otherwise heat treated may vary greatly, the members 96 are made in substantially the shape shown in Fig. 8 in order that the spacing between them and, therefore, between the hooks 98, may be such as may be desired.

75 The members 58, each of substantially Z-shape and defining the upper edges of the walls of the slots 41 and 42, are severally provided with dust-collecting grooves 101 in their upper horizontal surfaces. Slot-closure means are also provided in the form of relatively narrow elongated metal plates 102, one of the ends of each of the plates being bent laterally out of the normal plane of the plate, 80 in substantially the manner shown in Fig. 7 of the drawings. Each plate 102 is provided with openings through which the upper end portions of the rods 91 may extend. During the normal operation of the furnace, the plates 102 rest upon the intermediate webs of the members 58, which members, as shown in Fig. 1 of the drawings, extend not only along the length of the furnace structure but also over all of the path traversed by the conveyer 85 chain.

90 While no specific details of the means for supporting the members 58 beyond the furnace structure are shown, it is to be understood that suitable supporting means are provided 95 and are spaced suitable distances apart.

95 Since dust is always present in the atmosphere and may drift downwardly through the slots 41 and 42 and possibly settle upon the articles undergoing treatment and thus impair their appearance, the dust grooves 101 in the members 58 and the plates 102 which to cover these grooves are provided to insure that the dust shall be caught in the grooves instead of being permitted to fall through the slot. Any suitable or desired means may be employed to remove the accumulated dust from the grooves 101 at suitable intervals of time.

100 Referring to Fig. 6 of the drawings, attention may be called to a relatively small mass of mineral wool 103 which covers not only the slot end of the mass 36 of concrete but also the upper end of the members 43. Material of this kind is provided at this place in order to 105

permit of vertical movement of the members 43 relative to the members 58, that is, any unequal expansion or contraction or relative movements of these members of the furnace structure will be of no effect, so far as alignment of these members is concerned, so that uninterrupted movement of the conveyer chain may be expected so long as it is desired to effect such continuous movement.

Any desired heating means may be provided but I prefer to utilize electric heating means and, for this purpose, I have provided a plurality of hanger blocks 106 extending into, and constituting a part of, the wall structure, one set of such refractory hanger blocks being located adjacent to the upper portion of the furnace chamber and a second set being located approximately midway of the vertical height of the furnace chamber, from which suitable resistor members 107 may be suspended. Refractory spacing members 108 are also provided in order to ensure that adjacent parts of the preferably metallic resistor member 107 shall not operatively engage each other during the operation of the furnace.

It is highly desirable to provide a bottom heating means and, for this purpose, I provide a resistor member 109 which is located immediately above the upper surface of the bottom portion or wall of the furnace and the adjacent convolutions of this resistor member are spaced apart by similar refractory members 108. A floor plate 111, preferably made of metal, is supported by suitable refractory supporting members 112 above the resistor 109. I have indicated the electric heating elements generally only and do not desire to be limited to any particular construction of such elements, inasmuch as the main object is to obtain substantially uniform heat distribution in the chamber from heaters adjacent to at least three walls of the furnace.

As was hereinbefore stated, the slot-closure plates 102 are to be supported by the continuity of members 58 extending not only over the furnace structure proper but also beyond it. In order to ensure a support for the plurality of slot-closure plates 102, in addition to that provided by the members 58, I have provided, on each of the depending rods 91, an intermediate annular flange 116 so that the plates 102 will be prevented from dropping downwardly upon the rods 91.

It may become necessary to shut down the furnace for repairs to the conveyer chain or chains, and, in order to be able to conserve the heat stored in the structure of the heating chambers, I provide a plurality of swinging doors 121, shown more particularly in Fig. 2 of the drawings, each door being hinged on horizontal trunnions 122 and being provided with a counterweight 123, the door assembly being turned by manual means (not shown) from its normal position, as shown in Fig.

2 of the drawings, to a substantially upright position, whereby the ends of the heated furnace chambers are substantially closed.

Side-door openings 126 are provided adjacent to the ends of the heated furnace chambers, and a door 127, of refractory material, is provided for each of the door openings. These doors may move vertically or swing horizontally as may be found desirable and I have not indicated any specific supporting means therefor.

The furnace structure embodying my invention thus provides a highly efficient wall structure including a number of layers or shelves of different refractory materials, each being located in that part of the furnace structure wherein it will effect or obtain the best results according to its own characteristics.

A metallic skeleton frame surrounds the furnace structure of refractory material, the upper part of the skeleton metal frame and particularly that part located over the refractory furnace structure being provided with a plurality of spaced but cooperating skeleton frames effective not only to support the conveyer chain, the material-supporting members and the material itself but operative also to support the overhanging parts of the roof structure of the furnace in such manner as to preclude appreciable movement of these parts relative to each other. I have found, in effect, in an actually installed and operated furnace, that the provision of these skeleton frames located within, and adjacent to the top portion of, the main skeleton frame ensures that the overhanging roof portions will move but a very small fraction of an inch, if at all, in spite of the fact that the temperature coefficients of expansion of the different materials may vary quite widely. This means that there will be little or no shifting of the roof structure relative to the track located at the top of the skeleton-frame structure and it is, therefore, possible to vary the temperature of the furnace chamber in accordance with possible demands for such change or to shut down the furnace and then start the same again without experiencing any trouble because of mechanical engagement of the moving parts and the stationary parts by reason of such relative expansive or contractive movements.

The slot-closure plates 102 are moved by the rods 91 but are supported by the furnace structure to not only close the slots 41 and 42 but also to prevent dust particles from settling on the work being carried through the furnace chambers, so that a relatively large proportion of perfectly enameled material is ensured.

Since various modifications may be made in the device embodying my invention, I desire that only such limitations shall be placed

thereon as are imposed by the prior art or are set forth in the appended claims.

I claim as my invention:

- 5 1. A tunnel furnace having outside walls of predetermined length and an inside wall of shorter length, a concrete base structure for all of said walls, and means anchored in said concrete base structure at the end of the inside wall for preventing free longitudinal expansion of said inside wall at its upper part.
- 10 2. A tunnel furnace having solid outside walls of predetermined length and an inside wall of shorter length and including a plurality of arched portions, a concrete base structure for all of said walls, and means anchored in the concrete at the end of said inside wall for forcing the longitudinal expansion of the inner wall to be expended in the arched portions thereof.
- 15 3. A double-chamber tunnel furnace having a central wall and side walls and a skeleton metal frame at the sides and the top of the walls, a roof structure including a plurality of refractory slabs having edge portions resting on one of said walls and overhanging the same and resilient means depending from the metal frame for supporting the overhanging refractory slabs.
- 20 4. A tunnel furnace having side walls, a longitudinally-slotted roof structure including a plurality of horizontally-extending refractory slabs each having an edge portion resting on one of said walls, a plurality of vertically-extending refractory slabs resting on the other edge of said horizontally-extending refractory slabs, and a mass of initially plastic self-hardening material tying together the wall and the two sets of refractory slabs.
- 25 5. A tunnel furnace having longitudinally-extending walls, and a skeleton metal frame at the sides and the top of the furnace, a roof structure having a longitudinal slot and comprising horizontally-extending slabs of refractory material having their respective outer edge portions resting on one of said walls and their inner edges located in laterally-spaced relation at said slot, vertically-extending slabs of refractory material resting on the inner edge portions of the horizontally-extending slabs at said slot, and metal members of substantially angle-bar shape in lateral section supported by said skeleton metal frame and operatively engaging the upper edge portions of said vertically-extending slabs to maintain a predetermined distance between the upper ends of said vertical slabs while permitting free vertical expansion thereof.
- 30 6. A double-chamber tunnel furnace having two outside walls and one intermediate wall to constitute two parallel and longitudinally-extending chambers, and a skeleton metal frame, a three-part roof structure, each part having at least one portion thereof supported on one of said walls and having another por-

tion overhanging one of said furnace chambers, three diagonally-braced box-like frames above said roof structure and supported by the skeleton metal frame, and resilient means supported from the box-like frames and supporting the respective overhanging portions of the roof structure.

In testimony whereof, I have hereunto subscribed my name this 28 day of Feby. 1930.

JAMES C. WOODSON.
